UNITED STATES PATENT OFFICE.

SAMUEL H. SERLIN, OF CHICAGO, ILLINOIS.

DESIGN FOR AN AMPLIFYING HORN.

Application filed September 19, 1924. Serial No. 10,829. Term of patent 14 years.

To all whom it may concern:

Be it known that I, SAMUEL H. SERLIN, a citizen of the United States, resident of Chicago, county of Cook, and State of Illinois, have invented a new, original, and ornamental Design for Amplifying Horns, of which the following is a specification, reference being had to the accompanying drawing, forming a part thereof, wherein:

Fig. 1 is a front elevation of the amplifying horn, showing the same in position on a support; and

Fig. 2 is a side elevation thereof.

I claim:

The ornamental design for an amplifying horn, as shown.

SAMUEL H. SERLIN.
